UNITED STATES PATENT OFFICE.

PERCY TRIPP BAILEY, OF MIDDLETOWN, RHODE ISLAND.

POST-ANCHOR.

1,107,016.

Specification of Letters Patent. Patented Aug. 11, 1914.

Application filed October 23, 1913. Serial No. 796,921.

To all whom it may concern:

Be it known that I, PERCY TRIPP BAILEY, a citizen of the United States, and a resident of Middletown, in the county of Newport 5 and State of Rhode Island, have invented a new and Improved Post-Anchor, of which the following is a full, clear, and exact description.

This invention relates to improvements in 10 post anchors, and particularly to an improved anchor which may be readily clamped in position at any time, and at any desired point along the post, whereby the post may be set any desired distance in the 15 ground.

The object in view is to provide an improved structure readily clamped to a post at any point formed with clamping portions for clamping bracing arms to the post.

20 A further object of the invention is to provide a simple, strong and inexpensive clamping structure for bracing arms which may be quickly applied and removed, and which cannot get out of order.

25 In carrying out the object of the invention the anchor may be connected with any kind of post, as for instance a round post. The clamping device comprises a pair of clamping arms formed with substantially 30 A-shaped depressions for receiving angle irons, and clamping the same to the post. These clamping members are rigidly held in place by a clamping member at each end which is preferably in the nature of a bolt.

35 In the accompanying drawing—Figure 1 is a side view of the lower end of a post with an anchor embodying the invention applied thereto; Fig. 2 is an edge view of the structure shown in Fig. 1; Fig. 3 is a top 40 plan view of the structure shown in Fig. 1.

Referring to the accompanying drawing by numeral 1 indicates a post preferably round as shown in Fig. 3. In order to hold this post properly in place anchoring arms 45 2 and 3 are provided, and are rigidly clamped to post 1 by clamping bars 4 and 5. The anchoring arms 2 and 3 are angle irons, and are arranged at any desired angle to the post 1, the angle being controlled by the 50 pressed-out portions 6 and 7 on the clamping members 4 and 5. It will be observed that the clamping members 4 and 5 are of identical construction, whereby when they are arranged as shown in Fig. 3 the pressed-out 55 portions of one bar will extend diagonally in one direction, and the pressed-out

portion of the other bar will extend diagonally in another direction, so that the arms 2 and 3 may be properly forced into the ground at each side of the post. Suitable 60 clamping members, as for instance, bolts 8 and 9 are provided for moving bars 4 and 5 toward each other, and thereby firmly clamping arms 2 and 3 in position.

In assembling the arms 2 and 3, and the 65 clamping members 4 and 5, the clamping members are preferably loosely clamped around post 1, and then arms 2 and 3 are driven into the ground, the arms passing between the post 1 and the pressed-out portions 70 6 and 7, respectively. In this way the arms are guided and properly held in position adjacent the post. After the arms 2 and 3 have been driven into the ground the desired distance bolts 8 and 9 are then tightened, 75 whereby the pressed-out portions 6 and 7 will press the edges of the arms 2 and 3 against post 1, and will also engage post 1 at points 10 and 11. The apertures through which the bolts 8 and 9 are passed are preferably somewhat larger than the bolts so that the clamping bars 4 and 5 may properly adjust themselves to the post, and to the clamping arms. From Fig. 1 it will be 80 observed that the clamping arms extend 85 transversely or at right angles to the post 1, while the arms 2 and 3 extend at almost a 90° angle. This angle may be varied by varying the twist or angle of the pressed-out portions 6 and 7.

90 What I claim is:

1. In a post anchor of the character described, a pair of clamping members extending transversely of the post, formed with socket portions for receiving and pressing anchoring arms against said post and means arranged at each end of the clamping members for drawing the clamping members toward each other.

2. In a post anchor of the character described, the combination with a round post, of a pair of clamping bars extending transversely of the post, each of said clamping bars being formed with a pressed-out portion having a groove extending at an angle 105 to the post for receiving an anchoring arm, and means for clamping said clamping bars and the anchoring arm carried thereby against said post.

3. In a post anchor of the character described, a pair of clamping bars of identical construction, each of said bars being formed

with a flat portion at the ends and a substantially A-shaped pressed-out portion centrally, said A-shaped pressed-out portion having the apex extending at an angle to the general direction of the clamping bar, said A-shaped pressed-out portion being designed to receive an anchoring arm, and means engaging the end of said clamping bars for holding the clamping bars in position and 10 pressing said anchoring arm against a post.

4. In an anchoring post of the character described, the combination with a pair of anchoring arms, of a pair of clamping bars for clamping said anchoring arms against a post, and means for holding said clamping bars in position, said clamping bars being each formed with a pressed-out portion extending at an angle to the general direction of the bars for accommodating one of said anchoring arms, and a flat portion formed with an aperture for accommodating said retaining means for the clamping bars.

5. In a post anchor of the character described, the combination with a round post, of a pair of anchoring arms formed of angle bars, a pair of clamping bars for holding said anchoring arms in position, and a bolt at each end of the clamping bars for clamping and holding the clamping bars in place, each of said clamping bars comprising a single piece of material having flattened ends with apertures formed therein larger than the bolts arranged therein, and with a pressed-out portion conforming to the shape of said anchoring arms, said pressed-out portion being arranged at an angle to the general direction of the clamping bars.

In testimony whereof I have signed my name to this specification in the presence of two subscribing witnesses.

PERCY TRIPP BAILEY.
